UNITED STATES PATENT OFFICE.

FREDERICK E. COTTRELL, OF PEPPERWOOD, CALIFORNIA.

SAFETY-HOOK.

1,168,482.

Specification of Letters Patent. Patented Jan. 18, 1916.

Application filed March 30, 1915. Serial No. 18,093.

To all whom it may concern:

Be it known that I, FREDERICK E. COTTRELL, a citizen of the United States, residing at Pepperwood, in the county of Humboldt and State of California, have invented 5 new and useful Improvements in Safety-Hooks, of which the following is a specification.

My present invention pertains to hooks 10 for swingletrees and the like; and it consists in the simple, durable and reliable safety hook hereinafter described and definitely claimed.

In the drawings, accompanying and forming 15 part of this specification: Figure 1 is a plan view showing my novel hook in use. Fig. 2 is a rear elevation of the same. Fig. 3 is an elevation of the outer end of the hook. Fig. 4 is a plan of the blank from which the 20 body of the device is preferably, though not necessarily, formed.

Similar numerals of reference designate corresponding parts in all of the views of the drawings.

25 On the end portion of the swingletree 1 is suitably fixed the body 2 which is provided with the hook 3; the said body being formed from the blank shown in Fig. 4, and the opposed layers of the hook 3 being connected by rivets 4. A trace is designed to 30 rest on the hook 3 and in the space between the hook and the outer end of the body 2, and for the purpose of guarding the mouth of the hook and precluding casual disconnection of the trace, I provide the retaining pin 7. The said pin 7 is movable endwise and also about its axis, and is provided at 35 8 with a laterally-disposed weight portion.

As best shown in Figs. 1 and 2, the pin 7 40 is arranged and movable in guides 5 and 6, and the lateral weight portion 8 is disposed and movable between the said guides. The guide 5 is arranged at right angles to the line of movement of the pin 7, and the guide 45 6 is arranged obliquely to said line for an important purpose hereinafter set forth.

50 Preferably, though not necessarily, the guides 5 and 6 are formed by staples; the said staples being driven through apertures in the body 2 and into the swingletree 1 so as to serve the additional purpose of securing the body 2 on the swingletree.

It will be manifest from the foregoing 55 that when the pin 7 is positioned as shown in Figs. 1 and 2, the weight portion 8 will tend to rest in the pendent position shown, and

will bear against the part of the guide 6 nearest the outer end of the body 2. In consequence of this the pin 7 will be effectually held against endwise movement inwardly 60 on the body 2, with the result that there is no liability of the mouth of the hook being left unguarded, and no liability of the trace becoming accidentally disconnected from the hook. When, however, it is desired for the 65 mouth of the hook to be opened, as when a trace is being placed on or removed from the hook, the same is accomplished by the operator rocking the pin 7 about its axis until the weight portion 8 is in or above the 70 horizontal, and then moving the pin 7 endwise inwardly relative to the body. When the weight portion 8 is positioned as stated it will be manifest that a considerable inward endwise movement of the pin 7 may 75 be effected without interference from the guide 6, and this notwithstanding that when the weight portion 8 is arranged as shown relative to the guide 6 the said coöperating parts will effectually prevent accidental inward movement of the pin. 80

The construction herein illustrated and described constitutes the best practical embodiment of my invention that I have as yet devised. I do not desire, however, to be understood as confining myself to the specific construction and relative arrangement of parts inasmuch as in the future practice of the invention such changes or modifications may be made as fairly fall within the scope 85 90 of my appended claims.

Having described my invention, what I claim and desire to secure by Letters Patent, is:

1. In means for the purpose described, 95 the combination of a swingletree, a body mounted on the end portion thereof and having a hook spaced from its outer end, staples driven through the body and into the swingletree; the said staples constituting fastening devices and guides, and the staple nearest the outer end of the body being disposed at right angles thereto and the other staple being disposed obliquely to the body, and a pin for guarding the mouth of the hook, said pin being movable endwise and about its axis in the guides and being provided with a laterally-disposed weight portion arranged between the guides. 100

2. The combination of a swingletree, a body carried by the swingletree and having a hook the mouth of which is beyond the 105 110

end of the swingletree, a staple driven through the body and into the swingletree and disposed obliquely to the body, guiding means carried by the body and arranged in spaced relation to the staple and between said staple and the mouth of the hook, and a pin for guarding the mouth of the hook; said pin being movable endwise and about its axis in said staple and guiding means and being provided with a laterally-disposed

weight portion arranged between the staple and the guiding means.

In testimony whereof I have hereunto set my hand in presence of two subscribing witnesses.

FREDERICK E. COTTRELL.
